UNITED STATES PATENT OFFICE.

WILLIAM T. TRUAX, OF BATTLE CREEK, MICHIGAN, ASSIGNOR TO UNITED STATES REGISTER COMPANY, OF BATTLE CREEK, MICHIGAN, A CORPORATION OF MICHIGAN.

REGISTER-DAMPER-OPERATING DEVICE.

Application filed December 10, 1924. Serial No. 755,356.

To all whom it may concern:

Be it known that I, WILLIAM T. TRUAX, a citizen of the United States, residing at Battle Creek, in the county of Calhoun and State of Michigan, have invented certain new and useful Improvements in Register-Damper-Operating Devices, of which the following is a specification.

This invention relates to register damper operating devices. More particularly it belongs in the class with warm air wall registers, and concerns the devices for swinging the damper or gate towards and from the grating or open-work front of the register, according as it is desired to shut off the warm air from the room or direct it into the room through the front grating.

The object of this invention is to provide a lever device and related members each of special construction and arrangement with respect to another, whereby the register damper may be held open or closed or in any intermediate position by a spring clasp, which permits the changing of the inclination of the damper when desired easily and without the exertion of other than a light pressure of the fingers. It is further an object of this invention to produce a contrivance of the nature stated that will enable the various parts in the process of manufacturing to be conveniently and quickly assembled or erected, in order that the total cost of production in commercial quantities may be reduced as far as practicable.

In the accompanying drawings the special construction and preferred arrangement of the parts of this invention are illustrated. Fig. 1 represents a front view of a register to which this invention is applied, and shows the position of the finger piece of the operating lever in the register front. Fig. 2 is a rear view, showing the parts inside the register front or frame. Fig. 3 is a side view. Fig. 4 is a vertical section on the broken line 4—4 of Fig. 2, the parts drawn being shown full size to render the illustration clearer. Fig. 5 is a front view of a portion at the middle of the flanged stiffening piece arranged horizontally on the inside of the register front, and shows the projecting portion of the flange, with the downwardly extending rigid part, and the spring attached to the projecting member and arranged adjacent to the rigid portion. Fig.

6 is a top view of the middle portion of the horizontal stiffening member shown in Fig. 5, and illustrates the extended or projecting portion of the flange. In this view the spring is omitted. Fig. 7 is a vertical section of the register front on the same line as stated for Fig. 4, but showing the damper open, and the position of the operating lever then assumed. In Fig. 4 those parts are represented in the positions reached when the damper is closed, that is to say, moved to cover the opening in the register front over which the grating extends. Fig. 8 is a vertical section of the register front taken on the broken line 8—8 of Fig. 2.

Throughout the drawings and description the same letter is used to refer to the same part.

Considering the drawings, the front A of the register, has the usual opening for the passage outward of the warm air, covered by the grating or openwork a. The finger piece of the operating lever B is shown projecting before the front A, and movable in the slot b in the front through which the lever passes.

On the inside of the front A is the damper C, and along its upper edge the damper has the usual rounded and wired termination c. As best shown in Figs. 4 and 7, the operating lever B has a rounded recess D, which takes in the rounded and pivoted upper edge of the damper. It may be stated here that the recess engages the rounded edge c, which is the fulcrum of the lever B. The lower end d of the lever is pointed or wedge-shaped and is passed through the damper C as illustrated to secure the end to the damper.

Besides the finger piece or portion which passes through the front A as shown, the lever B has an extended flat portion E intersected by a straight upper edge resulting in a corner or angle e. It will be noted in Figs. 2, 4 and 7, that the flat extension E of the body of the lever B is clasped between the flat spring F and the rigid downwardly extending portion f of a projection G of the flanged member g. The extension E, as will be understood, is always in the frictional grasp of the spring clasp, and is thereby yielding held in any position either open or closed or intermediate. The parts just described relating to the spring clasp and

to the flanged member *g* are also shown in Figs. 5 and 6.

The flanged member *g* is a stiffening piece or bar, and as shown in Fig. 2, and in Fig. 8, extends horizontally upon the inside of the front *A* just above the grated opening. It is usually attached to the front by rivets or spot welding. In practice, side stiffening strips *H* and *h* are attached vertically on the inside of the front *A*, as shown in Fig. 2.

To support or hang the damper *C* movably, as shown in Figs. 2, 4, 7 and 8, the web of the flanged member *g* is extended downwardly to form the hangers *J*, which encircle the rounded edge *c* of the damper at usually two points as illustrated, thereby supporting the damper pivotally upon and within the front *A*. This invention is not limited to the particular devices set forth for pivotally holding the rounded upper edge of the damper, as that arrangement is readily modified.

The above description is the same in all respects as the description set forth in the abandoned application for the same invention filed April 23, 1921, Serial Number 463,983.

In the operation of this invention, it will be understood as already explained that the frictional grasp of the spring *F* and the rigid portion *f* of the projecting part of the flanged member *g* is constant, and will hold the damper at any point. But little effort upon the finger piece of the lever *B* is called for to move the damper. When the air is to be shut off from the room, the damper is moved to cover the grating or openwork *a* of the front, and the closing movement is limited by contact with the front. When the warm air is to be directed into the room through the grating *a*, the damper is swung into the position illustrated in Fig. 7, and it will be noted that the opening movement will be brought to a stop when the corner *e* of the flat extension *E* of the lever *B* strikes the projection *G* of the flange of the member *g*. Furthermore, it will be noted that, for convenience and rapidity of assembling in the process of manufacture, the lever and damper may be assembled and placed in position, and the hangers *J* bent about the rounded edge *c* of the damper with practically a minimum of labor and time.

Having now described this invention and explained the mode of its operation, what I claim is:

1. In a register damper operating device, the combination with a register front, of a projecting member attached to the front inside thereof, the said projecting member having a rigid portion extending downwardly, a spring attached to the projecting member and arranged facing the said rigid portion, a damper having an upper edge pivotally supported by the said front, a

lever having a recess engaging the said upper edge of the damper as a fulcrum, the said lever having a finger piece passing through the front and an extension inside of the front arranged between the said spring and the rigid portion of the projecting member and in frictional contact with them, and the said lever having an end secured to the said damper.

2. In a register damper operating device, the combination with a register front, of a horizontal stiffening member attached to the said front on the inside thereof, the said member having an extended flange provided with a rigid portion extending downwardly, a spring attached to the said extended flange and arranged facing the said rigid portion, a damper having an upper edge pivotally supported by the said front, a lever having a recess engaging the said upper edge of the damper as a fulcrum, the said lever having a finger piece passing through the front and an extension arranged between the said spring and the rigid portion of the said member and in frictional contact with them, and the said lever having a lower end secured to the said damper.

3. In a register damper operating device, the combination with a register front, of a projecting member attached to the front on the inside thereof, the said projecting member having a rigid portion extending downwardly, a spring attached to the projecting member and arranged facing the said rigid portion, a lever having a finger piece passing through the said front and an extended portion within the front frictionally engaging the said spring and the rigid portion of the said member, a damper, the upper edge of the damper being pivotally attached to the said front, and the said lever being fulcrumed upon the pivoted edge of the damper and having its lower end attached to the damper.

4. In a register damper operating device, the combination with a register front, of a projecting member attached to the front inside thereof, the said projecting member having a rigid portion extending downwardly, a spring attached to the projecting member and arranged facing the said rigid portion, a lever having a rounded recess, the said lever having a finger piece passing through the said front and an extended portion within the front frictionally engaging the said spring and the rigid portion of the said member, a damper having its upper edge pivotally attached to the said front, the said rounded recess of the lever being arranged adjacent to the said pivoted upper edge of the damper, and the lower end of the lever being secured to the damper.

In testimony whereof I affix my signature.

WILLIAM T. TRUAX.
